ARLEN J. BROWN, OF ERIE, PENNSYLVANIA.

TRAP.

Application filed November 29, 1926. Serial No. 151,332.

In the catching of many animals, such for instance as muskrats, the ordinary box traps are not satisfactory for several reasons, one, that they cannot be usually properly placed with relation to the runs. It is also desirable with such traps that they be buoyant enough to be placed on the water. It is desired to catch the animals without injury so that ample space for the box to operate is desirable and for this reason also a comparatively light box is desirable. Features and details of the invention will appear from the specification and claims.

The invention is illustrated in the accompanying drawings as follows:—

Fig. 1 shows a plan view, partly broken away.

Fig. 2 a section on the line 2—2 in Fig. 1.

1 marks the base which is of buoyant material, as wood, and 2 the box which is preferably of light wire mesh mounted on a wire ring 3. At one edge of the box hinged straps 4 extend around the ring and form a hinge on which the box may be swung to elevated position. The ends of the ring are projected rearwardly forming a trigger projection 5.

A trigger latch 6 is pivotally mounted on the base by means of a staple 7. A trigger 8 has the rear end bent downwardly at 9 and is pivotally secured to the base by staples 10. A bait plate 11 is formed on the trigger.

The downward bend 9 has a small opening 9^a. With the box elevated the latch 6 may be carried over the trigger projections 5 and the trigger lifted so that the latch extends into the opening 9^a. The weight of the box holds the bait pan in its upper position. When the pan is depressed this releases the latch and drops the box.

Inasmuch as the top is comparatively light it is desirable to lock the box after it is dropped and this is accomplished by the lock 12. This is arranged in a slot 13 in the base and pivotally secured to the base by a staple 14. It has a hook 15 which engages the ring 3 when it drops to lower position and has a forward projection 16 which forms a weight drawing the lock into engaging position.

It is desirable to accelerate the closing of the box and this is accomplished by a spring 17 which is coiled around the hinged edge of the ring, one end of the spring

being anchored at 18 on the base and the opposite end 19 on the side reach of the ring.

What I claim as new is:—

1. In a trap, the combination of a base; a box hinged at one edge on the base; a trigger projection on the hinged edge of the box; and a trigger operating on the projection for holding the box in open position when set and releasing the same on the operation of the trigger. 65

2. In a trap, the combination of a base; a box hinged at one edge of the base, said box being formed of wire mesh with a surrounding ring at its lower edge, said ring having a trigger projection; and a trigger operating on the projection for holding the box in open position and releasing the same to permit the closing of the box when the trigger is operated. 70

3. In a trap, the combination of a base; a box hinged at one edge of the base, said box being formed of wire mesh and a ring along its bottom edge, the adjoining ends of the ring extending rearwardly forming trigger projections; and a trigger operating 75 on the projections for holding the box in open position when set and permitting the box to close when the trigger is operated. 80

4. In a trap, the combination of a base; a box arranged at one edge of the base; a trigger projection on the hinged edge of the box; a trigger operating on the projection and holding the box in open position when set and releasing the same on the operation of the trigger; and a spring on 90 the hinged edge accelerating the closing of the box. 85

5. In a trap, the combination of a base; a box hinged on the base; and a trigger mechanism for holding the box in open position and permitting the box to close when operated, said base being of buoyant material and adapted to maintain the trap with the upper surface of the base above water with the trap floating whereby the animal 95 trapped may be supported by the buoyancy of the base and caught uninjured. 100

6. In a trap, the combination of a base; a box hinged on the base, said box being formed of wire mesh with a surrounding ring at its edge, said ring having a trigger projection at the hinged edge; and a trigger engaging the projection and holding the box in set position to permit the box to close when operated, said base being of sufficient 105 110

buoyancy to float the trap with the upper surface of the base above water.

7. In a trap, the combination of a base; a box hinged on the base; a trigger mechanism for holding the box in open position and permitting the box to close when operated, said base being of buoyant material and adapted to maintain the trap with the upper surface of the base above water with the trap floating whereby the animal trapped may be supported by the buoyancy of the base and caught uninjured; and a catch for locking the box in closed position.

8. A device of the class described comprising a float adapted when placed in water to support the weight of the device and a captured animal; a cage open at its underside only and hinged at one edge thereof on the float; spring means tending to swing down the cage; a detent adapted to hold it in a raised position; and a trigger for releasing the detent located within the cage close to the hinged end but leaving sufficient room for the animal between the trigger and the opposite end of the cage.

9. A device of the class described comprising a float adapted when placed in water to support the weight of the device and a captured animal; a rectangular frame hinged at one side on the float; an open bottomed cage secured to said frame; a pro-

jection of the aforesaid side of the frame extending outside the cage; a detent hinged on the float outside the cage and adapted to extend inside the cage over said projection to hold the cage in a raised position; and a trigger hinged on the float adapted to be engaged by the detent to hold the latter in its projection engaging position, the trigger being located within the cage close to the hinged end but leaving sufficient room for the animal between the trigger and the opposite end of the cage.

10. A device of the class described comprising a base; a rectangular frame hinged at one side on the base; an open bottomed cage secured to said frame; a projection of the aforesaid side of the frame extending outside the cage; a detent hinged on the base outside the cage and adapted to extend inside the cage over said projection to hold the cage in a raised position; and a trigger hinged on the base adapted to be engaged by the detent to hold the latter in its projection engaging position, the trigger being located within the cage close to the hinged end but leaving sufficient room for the animal between the trigger and the opposite end of the cage.

In testimony whereof I have hereunto set my hand.

ARLEN J. BROWN.
